(57) CLAIM

The ornamental design for a shoe as shown and described.

DESCRIPTION

FIG. 1 is a front perspective view of a shoe showing our new design;

FIG. 2 is a side view thereof;

FIG. 3 is an opposite side view thereof;

FIG. 4 is an opposite side front perspective view thereof;

FIG. 5 is a top view thereof;

FIG. 6 is a front view thereof;

FIG. 7 is an enlarged view encompassing the claimed region of FIG. 1 with environment outside the disclaimed boundary removed for clarity purposes;

FIG. 8 is an enlarged view encompassing the claimed region of FIG. 2 with environment outside the disclaimed boundary removed for clarity purposes;

FIG. 9 is an enlarged view encompassing the claimed region of FIG. 3 with environment outside the disclaimed boundary removed for clarity purposes;

FIG. 10 is an enlarged view encompassing the claimed region of FIG. 4 with environment outside the disclaimed boundary removed for clarity purposes;

FIG. 11 is an enlarged view encompassing the claimed region of FIG. 5 with environment outside the disclaimed boundary removed for clarity purposes; and,

FIG. 12 is an enlarged view encompassing the claimed region of FIG. 6 with environment outside the disclaimed boundary removed for clarity purposes.

The broken lines immediately adjacent to and surrounding the photographic area define the peripheral bounds of the claimed design and form no part thereof. The broken lines depicting the remainder of the shoe form no part of the claimed design.

1 Claim, 12 Drawing Sheets
